HANDLE MOUNTING FOR NET FRAMES

Robert Conrad, Burbank, Calif.

Application August 27, 1954, Serial No. 452,495

6 Claims. (Cl. 306—45)

The present invention relates to a device particularly adaptable as a swimming pool skimmer head and as an angler's net.

An object of the invention is the provision of a handle or pole mounting for net frames, which net frame is quickly and easily attached or detached from the handle.

A further object is the provision of a handle or pole mounting for a net frame which is rigid in structure, inexpensive in cost of manufacture, simple of construction, and generally superior to net devices now known to the inventor.

In the drawings:

Figure 1 is a perspective view of the device of the invention as an entirety.

Figure 2 is a transverse sectional view, partly in fragment, and on an enlarged scale, of the handle or pole casting or head, showing the method of attachment therewith of the net bow or frame.

Figure 3 is a fragmentary sectional view on the line 3—3 of Figure 2.

Figure 4 is a fragmentary perspective view, partly in section, showing the net bow or frame attached to the pole casting or head, and,

Figure 5 is a fragmentary perspective view, partly in section, showing the net bow or frame detached from the pole casting or head.

Referring now with particularity to the drawing, I have shown in Figure 1, a pole 1 provided with a casting or head 2, and a bow or frame 3 detachably secured to said casting or head 2, which bow or frame carries a basket type net 4. As is customary, the net is provided with a looped top so as to receive the bow or frame 3. Thus, the angler or the workman who desires to skim the debris, such as leaves, from the surface of a pool, may grasp the handle 5 of the pole and entrap the debris within the net 4.

The head or casting 2 is provided with two transverse bores 6 and 7, the bores being in axial alignment, and with longitudinal bores 8 and 9 which are substantially parallel and in right angular relationship to the bores 6 and 7. The said casting or head is provided with a transverse slot 10, which communicates with the bores 6 and 7. The width of the slot 10 is less in measurement than the diameter of the bores 6 and 7.

The bow or frame 3 is a loop of wire rod bent into split ring form and is provided with two straight portions 11 and 12 adapted to be in axial alignment and with two parallel end extensions or mounting shanks 13 and 14, in substantially right angular relationship to the portions 11 and 12. The diameter of the portions 13 and 14 is such as to permit passage thereof through the slot 10 for reception within the bores 8 and 9. Carried upon the portions 11 and 12 of the bow or frame 3 are sleeves 15 and 16. These sleeves have a diameter substantially equal to the diameter of the bores 6 and 7 so that the sleeves may be pressed within the bores 6 and 7 in the manner shown in Figure 2, to anchor the frame to the casting or head 2.

Preferably, the pole 1 is tubular and closed at one end by the handle 5, and the opposite end by the casting or head 2 so that the device, as an entirety, may float upon the surface of water. The pole is quite light and generally of considerable length.

The operation, uses and advantages of the invention just described are as follows:

The net is first secured to the bow or frame 3 in the usual manner, with the sleeves 15 and 16 slid upon the portions 11 and 12 to such position as to allow the extensions 13 and 14 to be passed through the slot 10 for reception in the bores 8 and 9 with portions 11 and 12 of the bow or frame passing through said slot 10 into bores 6 and 7. The sleeves 15 and 16 are then moved into the bores 6 and 7 in the manner shown in Figure 4, which will hold this portion of the bow or

2

frame to the casting or head 2. The bow or frame cannot be detached from the casting or head 2 unless the sleeves 15 and 16 are moved outwardly from the bores 6 and 7. The extensions 13 and 14 of the bow or frame 3 hold the curved portion thereof in the position shown in Figure 1 without appreciable bending. If it is desired to replace the net or to detach the bow or frame and its net from the pole, the operator, by a simple tool passed through the slot 10, may contact the ends of the sleeves 15 and 16 and slide the same upon the portions 11 and 12, whereupon the parts may be moved to the position shown in Figure 5.

Another feature of the present invention lies in the fact that any slack material in the said net may be pressed within the slot 10, thus supporting the net at this zone.

The device is attractive in appearance, different size bows or frames may be secured to the casting 2, as well as different shapes of bows or frames to serve any individual requirement.

I claim:

1. A device of the character described including a length of wire forming a net frame with two ends of the wire extending outwardly in the plane of the frame, roughly normal to the proximate portions of the frame, to provide mounting shanks for the frame, a sleeve slidable on each of said proximate portions toward and away from its shank, and a handle slotted to receive the shanks and also a part of each of said proximate portions and having two smaller bores to receive the shanks and two larger bores communicating with the smaller bores and with the slotted portion and each larger bore being adapted to receive one of the sleeves, said sleeves being too large to enter the slotted portion of the handle, whereby when the two sleeves are moved away from the shanks, the shanks may readily pass through the slotted portion in the handle into the two smaller bores and when the shanks are in such position the sleeves may be moved into the larger bores and toward the shanks and thus lock the net frame to the handle.

2. The device of claim 1 in which the sleeves when in locked position extend beyond the side margins of the handle.

3. The device of claim 1 in which the smaller bores are parallel, and the larger bores and the proximate portions of the frame are co-axial.

4. The device of claim 1 in which the slotted portion extends across the face of the handle, the larger bores and the proximate portions of the frame are co-axial and the distance of either smaller bore to the near side of the handle is roughly equal to the distance between the smaller bores, the latter being parallel to the sides of the handle while the larger bores extend inwardly from said sides.

5. A device of the character described comprising a frame including a split loop with angularly extending mounting shanks at the split, the portions of the loop adjacent the shanks being aligned, a head formed with a transverse slot at its free end, a pair of smaller longitudinal bores to receive the shanks and a pair of larger transverse bores extending inward from opposite sides of the head for each to communicate with one of the longitudinal bores and with the slot, and means slidable on the aligned portions of the loop and adapted to enter the transverse bores to lock the frame to the head, said means being too large to enter said slot.

6. In combination a rod having at right angles thereto a shank, a sleeve slidable on said rod adjacent the shank, and a holding member having therein a smaller bore receiving snugly the shank, a larger bore receiving snugly the sleeve, and a slot communicating with the larger bore, the slot readily receiving the shank and a proximate portion of the rod but being too narrow to receive the sleeve whereby when the sleeve is moved away from the shank, the shank and said proximate portion of the rod may be moved into the slot and the shank into the smaller bore, and when the sleeve is then slipped into its bore the rod will be locked to the holding member.
